UNITED STATES PATENT OFFICE.

HENRY MALIN, OF JOHANNESBURG, TRANSVAAL, SOUTH AFRICA.

DESIGN FOR A COMBINED DESK SET AND LAMP.

Application filed July 18, 1924. Serial No. 10,178. Term of patent 7 years.

To all whom it may concern:

Be it known that I, HENRY MALIN, a subject of the King of England, residing at Johannesburg, in the Province of Transvaal, South Africa, have invented a new, original, and ornamental Design for Combined Desk Set and Lamp, of which the following is a specification, reference being had to the accompanying drawing, forming part thereof.

The figure is a perspective view of a combined desk set and lamp showing my new design.

I claim:

The ornamental design for a combined desk set and lamp, as shown.

HENRY MALIN.
